TABLE

Adrian M. Pearsall, Forty Fort, Pa., assignor to Craft
Associates, Inc., Wilkes-Barre, Pa., a corporation of Pennsylvania

Filed June 10, 1964, Ser. No. 80,353

Term of patent 14 years

(Cl. D33—14)

The dominant features of my design reside in those portions shown in full lines in the drawings.

I claim:

The ornamental design for a table, substantially as shown and described.
